UNITED STATES PATENT OFFICE.

FRANK, A. LUNDQUIST, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,252,464.

Specification of Letters Patent.

Patented Jan. 8, 1918.

Application filed March 3, 1917. Serial No. 152,238.

To all whom it may concern:

Be it known that I, FRANK A. LUNDQUIST, a citizen of the United States, residing at Chicago, in the county of Cook and State of Illinois, have invented certain new and useful Improvements in Telephone-Exchange Systems, of which the following is a full, clear, concise, and exact description.

This invention relates to telephone exchange systems, and more particularly to automatic switches of the type employed in such systems.

The object of the invention is to provide a new and improved selector switch which shall be rapid in operation and which may be controlled in three selective movements by any standard substation impulse sending device.

In accordance with this invention, called line terminals are arranged in flat panels of the well-known type, and a set of brushes is provided to coöperate with each panel. The brush sets in each switch are spirally arranged on a shaft so that brush selection may be accomplished by rotation of the shaft. A stop shaft, arranged for longitudinal and rotary movements, and provided with a set of spirally arranged lugs, is elevated in the second selective movement of the switch and is rotated in the third movement so as to bring one of the lugs into position to be engaged by a stop arm carried on the brush shaft. The brush shaft is released and allowed to fall under the control of a governor during the rotation of the stop shaft so that, at the end of such rotation, the selected brushes will have been moved close to the selected terminals, and will come to rest on said terminals almost immediately. Restoration of both brushes and stop shafts may be accomplished by a single power driven wheel under the control of a release magnet.

The accompanying drawing shows a side elevation of a switch embodying the principles of the invention and such portions of operating circuits therefor as are necessary to an understanding of its operation.

The lines 1 and 2 from a preceding selector switch are multiplied to a plurality of sets of brushes 3, one such set being provided to coöperate with each panel of the

contact bank shown at 4. The brushes 3 are fixed to and arranged spirally about a shaft 5, being spaced apart a distance equal to the distance from the top of one panel to the top of the next panel. A gear wheel 6 is carried by a bushing 7 at the lower end of the shaft 5, the bushing 7 being splined to the shaft so as to rotate therewith but to be unaffected by longitudinal motion thereof. An auxiliary shaft 8, rotatably mounted in any convenient manner, is positioned so that a pinion 9, fixed rigidly at its upper end, will mesh with the gear wheel 6. A spiral spring 10, one end of which is held by a pin 11, tends to rotate the shaft 8 in a counter-clockwise direction, but the shaft is normally held against rotation by the engagement of a pawl 12 with lugs 13 carried on the gear wheel 6. The pawl 12 has two arms and is pivoted at 14 so that, when operated, it will allow the escape of the shaft 8, and the consequent rotation of brush shaft 5. The lugs 13 are placed alternately on the upper and lower faces of the wheel 6, the distance between lugs corresponding to the angle between successive brushes 3 so that each step of the pawl 12 will successively bring the sets of brushes into operative relation with the terminal banks 4.

A stepping magnet SM is provided with an armature 15 for actuating the switch. The armature 15 is pivotally mounted at 16 and has pivoted to its upper end a lever 17. A hook 18 at the end of lever 17 engages the pawl 12 so long as the rod 19 holds lever 17 in normal position, but is idle after the rod 19 has been depressed one step. The rod 19 has at its lower end a rack 20 which meshes with teeth 21 of a pinion 22. The pinion 22 has in addition a set of ratchet teeth 23 which are engaged by a stepping pawl 24 and a holding pawl 25. The pawl 24 is carried by the armature of a slow-release magnet 26 in such a way as to step the pinion 22 one step against the action of spiral spring 27 each time that the magnet 26 deenergizes.

A side switch 79 is provided to enable testing and ringing of the wanted line, but as it forms no part of the present invention, its controlling circuits are not shown.

A sleeve 28 is rotatably mounted on the auxiliary shaft 8 and is provided at its upper end with a rotary ratchet 29 and a vertical ratchet 30. A pin 31, fixed in the shaft 8, normally supports sleeve 28, while a spring 32 holds it in its normal rotary position. A series of lugs 33 project from the shaft 28 at equal intervals and are spirally arranged so that rotary steps of the shaft 10 will bring the lugs successively into the path of the stop arm 34. A pawl 35, carried by a lever 36, is arranged to rotate the ratchet 29, while a pawl 37, carried by the armature 15, co-operates with the ratchet 30 to elevate 15 sleeve 28. The pawls 38 and 39 are normally held out of engagement with ratchets 29 and 30 by cams 40 and 41, carried by the bushing 7, but will engage and hold their respective ratchets after the first 20 rotary step of the brush shaft 5. A lug 42, carried by the rod 19, holds the pawl 37 inoperative while the rod 19 is in normal position, but allows it to operate after the first downward step of said rod. After the 25 second downward step of the rod 19 a lug 43 holds pawl 37 inoperative. In this position of the rod 19 the end 77 of a lever 46 will be engaged between pins 47 of the lever 17.

30 The operation of the stepping magnet closes springs 48 intermittently and in position 2 of the rod 19 causes the elevation of the stop support 28. In position 3 of the rod 19 the operation of the stepping magnet imparts a to-and-fro motion to the 35 lever 46. The first attraction of the armature 15 at this time causes a catch 49 to become disengaged from an arm 50. Such motion of the lever 46 also actuates the pawl 40 35 to step the ratchet 29. The arm 50 may be the projecting end of a driving ribbon 51, which is secured to a bushing 52. The bushing 52 is rotatably mounted at the lower end 45 of brush shaft 5, but is held against vertical movement on said shaft in any convenient manner. Upon the removal of the catch 49 from the arm 50 the shaft 5 falls, its velocity being controlled by a governor indicated at 53, until the stop arm 34 comes 50 into engagement with the lug 33, which has been set in its path. The governor 53 may be of any desired type, being preferably arranged to control the downward movement 55 of ribbon 51, but to be held inoperative during upward movement of said ribbon.

During brush selection a pinion 54, rigidly mounted at the bottom of the shaft 8, will be rotated so as to move the rack 55 with which it meshes. The restoring magnet RM has an armature lever 56 pivoted at 60 57. A lever 58 is pressed by a spring 59 against a lever 60 which is pivoted to the armature 56. The movement of levers 58 and 60 is restricted by a pin 61 on rack 55.

After the first step of the rack 55 the lever 60 will engage a roller arm 62, and the switch 58 will advance to its second position. At this time the lug 65, at the end of rack 55, will allow the closure of contact springs 66. Upon the next step of the rack 70 55 the pin 61 will have been moved sufficiently to allow lever 60 to engage in its recess 64 the end of arm 62 when the restoring magnet RM becomes energized. Such a motion of the lever 60 allows the 75 switch 58 controlled by lever 58 to advance to position 3. A bell-crank lever 67 is pivoted at the upper end of armature 56 and is held in normal position by a pin 68 fixed to the ribbon 51. When in this position 80 lever 67 holds open the contact springs 69. Upon the downward movement of ribbon 51, pin 68 allows the lever 67 to drop into engagement with a lug 71 carried by a roller arm 72. When the magnet RM is energized, a 85 lug 73 on lever 67 will engage the lug 71 and force the roller arm 72 to the left, causing the roller 74 to press the ribbon 51 against the constantly rotating power driven wheel 75. When the ribbon 51 reaches normal 90 position, the engagement of the pin 68 with lever 67 causes the opening of contact springs 69, and the consequent deenergization of the release magnet and the return of roller 74 to its idle position. The de- 95 energization of the release magnet also causes the lever 60 to raise arm 62, which presses its roller 63 against rack 55. The rack 55, being pressed against power wheel 75, is moved to the right until it reaches 100 normal position, at which time the pin 61 draws lever 60 out of engagement with arm 62 and allows roller 63 to return to idle position. This movement of lever 60 also returns switch 58 to normal.

The operation of the switch is as follows: When a selector switch seizes a trunk leading to the connector switch it closes a circuit from grounded battery, through the winding of the stepping relay SR, conductor 2, 110 through the selector and line switches, through the substation apparatus, over the conductor 1 to ground. The consequent energization of relay SR closes a circuit from grounded battery, armature and front contact of relay SR, through the winding of slow-release relay 74 to ground. The subscriber now operates his dial to send a series of impulses which interrupt the circuit of the relay SR causing it to vibrate its armature. Each time that the relay SR retracts its armature it completes a circuit from grounded battery, armature and back contact of relay SR, through the winding of the stepping magnet SM, contact springs 45, front contact and armature of relay 74 to ground. The intermittent energization of the magnet SM operates the pawl 12 to allow 115 120 125

rotation of the brush shaft until the desired brush set is in operative relation with the contacts in the panel containing the terminal of the desired line. Upon the first attraction of armature 15 a circuit is closed from ground, through contact springs 48, winding of slow-release relay 26 to battery and ground. The relay 26, being slow, remains energized throughout each series of 5 impulses. At the end of the first series of impulses it deenergizes and steps the pinion 22 one step, thus lowering the rod 19 into position 2. The subscriber now sends another series of impulses, operating the magnet SM as before. Since the pawl 37 is now in operative relation to the ratchet 30, the stop shaft 28 will be elevated one step upon each attraction of the armature 15. At the 10 termination of this series of impulses the magnet 26 again deenergizes and the rod 19 is moved into position 3. The subscriber now sends the final series of impulses, causing as before, the operation of the stepping magnet. Upon the first attraction of the armature 15 the catch 49 is removed from the 15 arm 50 and the brush shaft 5 starts to fall under the control of governor 33. The continued operation of the armature 15 causes the rotation, in the manner previously described, of the stop shaft 28 until the desired lug 33 is placed in the path of stop arm 34. At completion of this series of impulses the deenergization of magnet 26 steps the rod 19 into position 4, at which time a lug 44, 20 carried by said rod, holds open the contact springs 45 so that an accidental operation of the stepping relay would not change the position of the switch. The shaft 5, which was falling during the setting of the lugs 33, 25 is arrested by the lug which has been placed in the path of arm 34 with its brush 3 in engagement with a desired line terminal, almost immediately after the completion of the final series of impulses. Testing and 30 ringing of the wanted line if idle now take place through contacts of the side switch 79 in any well-known manner, and the connection between the calling and called line is then complete. 35 At the close of the conversation the subscriber breaks at his switchhook the circuit for the stepping relay SR, which retracts its armature, breaking the circuit of relay 74, which thereupon deenergizes. In retracting its armature, relay 74 closes a circuit for the 40 release magnet RM from ground, armature and back contact of relay 74, contact springs 69, through the winding of the magnet RM and contact springs 66 to battery and ground. 45 The armature 56 of the magnet RM being attracted causes the vertical restoration of the brush shaft in the manner previously described. The armature 56, when attracted, also brought a rod 76 into engagement with 50 pawls 24 and 25, removing them from engagement with the teeth 23 so that pinion 22 is restored and moves the rod 19 back to its normal position. When the pin 68 engages, in its upward travel, lever 67, springs 69 are opened and the circuit for the release 55 magnet is broken. The lever 60 now causes the return of the rack 55 to normal in the manner previously described, and the rack 55 during restoration rotates shaft 8, winding up the spring 10 and turning gear wheel 75 6 back to normal. The pawl 12 is arranged so as not to obstruct the lugs 13 when the gear wheel 6 is moving in a counter-clockwise direction. When the rack 55 reaches normal the pin 61 restores levers 60 and 58, 60 in the manner described, and the switch is now in readiness for the next call. 65 Should the subscriber abandon the call before the release and downward movement of the ribbon 51, a circuit for the release 70 magnet would be completed from grounded battery, contact springs 66, winding of magnet RM, switch 78 in its second position, back contact and armature of relay 74 to ground. In attracting armature 56, the 75 magnet RM would break its own circuit, since switch 78 advances to its third position during the attraction of armature 56. The rack 55, rod 8 and brush shaft 5 would, 80 therefore, be restored as before. 95

What is claimed is:

1. In an automatic switch, a plurality of contacts, a plurality of brushes to coöperate with said contacts, a movable shaft to carry said brushes, means for selecting a set of 100 brushes, a rotatable rod, a plurality of stop members on said rod, means for initiating the travel of said brushes over said contacts, and means actuated during said travel for rotating said rod to position a selected stop 105 member to arrest said brushes on a selected contact.
2. In an automatic switch, a plurality of terminals, a plurality of brushes arranged to travel over and make contact with said 110 terminals, a stop arm associated with said brushes, a catch to normally prevent the travel of said brushes over said contacts, a movable rod, a plurality of stop members on said rod, means for selecting a brush to be 115 associated with said terminals, means for releasing said catch, and means operable subsequent to the release of said catch for positioning a selected stop member in the path of said stop arm, all of said means being 120 responsive to directive impulses.
3. In an automatic switch, a plurality of stationary contacts arranged in main groups and sub-groups, a movable shaft, a plurality of brush sets mounted thereon, means to operate said shaft to render one of said brush sets operative with relation to the main group of contacts served by it, a control 125

mechanism, a stop member carried thereby, means to position said control mechanism in response to a plurality of selective operations, means to advance a selected brush into engagement with a desired terminal in a desired sub-group in accordance with the setting of said control mechanism, and means

to advance said selected brush toward a desired position during the operation of setting said control mechanism. 10

In witness whereof, I hereunto subscribe my name this 28th day of Feb., A. D. 1917.

FRANK A. LUNDQUIST.
